UNITED STATES PATENT OFFICE.

ARTHUR MANHART, OF ELIZABETHTOWN, ILLINOIS.

SAW SET.

1,420,489.

Specification of Letters Patent. Patented June 20, 1922.

Application filed October 4, 1920. Serial No. 414,513.

To all whom it may concern:

Be it known that I, ARTHUR MANHART, a citizen of the United States, residing at Elizabethtown, in the county of Hardin and 5 State of Illinois, have invented certain new and useful Improvements in Saw Sets; and I do hereby declare the following to be a full, clear, and exact description of the invention, such as will enable others skilled 10 in the art to which it appertains to make and use the same.

The object of the invention is to provide a simple inexpensive and efficient saw setting mechanism particularly adapted for use 15 in connection with band saws, and having means of adjustment whereby it may be adapted for saws having different widths of blades and wherein the teeth are to be set at different angles or pitches; and with 20 these objects in view the invention consists in a construction and combination of parts of which a preferred embodiment is shown in the drawings wherein,

Figure 1 is a side view of the apparatus. 25 Figure 2 is a plan view of the same.

Figure 3 is a rear view.

Figure 4 is a longitudinal section on the plane indicated by the lines 4-4 of Figure 2.

30 Figure 5 is a transverse section on the plane indicated by the line 5-5 of Figure 1.

Figure 6 is a detail view perspective of the hammer.

The apparatus consists of a base 10 pref- 35 erably consisting of a solid and relatively substantial casting which carries the anvil 11 upon one end of which is pivotally mounted the hammer 12 yieldingly held in an ele- 40 vated position by the expansion spring 13.

45 Mounted for rotary adjustment in the ex- tension of the base forming said anvil is the gage 14 having the terminal discs 15 one of which carries a set screw 16 for securing the gage in its proper or adjusted position, the discs of the gage carrying the ears 17 being located respectively at opposite sides 50 of the surface of the anvil.

55 Mounted in advance of the front end of the anvil is a combined eccentric gage and guard disc 18 having a spindle 19 upon which it is mounted for axial sliding movement, said disc being provided with a sleeve 20 fitted upon the spindle and being yieldingly held in an elevated position, limited by the stop 60 or head 21 at the upper end of the spindle, by a spring 22 which is coiled upon the spin-

dle beneath the disc. Preferably the spindle consists of a screw which is threaded at its lower end in the upper end of a carrier 23 consisting of a block mounted to slide in a 60 guide 24 in the base, a jam nut 25 being employed to secure the spindle against rotary movement relative to the carrier. When the device is not being used for band saws the 65 loosening of the jam nut will permit of the removal of the disc and its spindle from the carrier.

The vertical movement of the carrier to effect the adjustment of the disc to secure the desired relation thereof to the saw which 70 is being formed and to the thickness of the saw blade, is accomplished by means of a feed screw 28 threaded in a suitable socket 29 in the lower end of the guide in which the carrier is mounted, and to lock the car- 75 rier in its adjusted position a set screw 30 is employed.

A locking pin 32 is carried by the head 21 to engage any one of a series of sockets 33 in the disk 18 to hold the latter against 80 rotation and in any of its adjusted positions. The disk 18 forms a combined gage and guard for the saw blade, whereby the in- 85 clination of the saw blade on the anvil may be varied to permit the teeth to be set at dif- 90 ferent desired angles or pitches, and to prevent the non-cutting edge of that portion of the saw blade lying at the anvil from moving upwardly when the teeth are struck by the hammer.

In operation, the lower run of the band saw blade is positioned as shown in Figure 1, the straight edge A of the disk 18 being disposed next to the anvil so that said por- 95 tion of the saw blade may pass slightly be- 100 low the disk to position one of the teeth on the anvil, it being understood that the saw blade is suspended from a suitable overhead structure (not shown). After the position- 105 ing of the saw blade, the disk 18 is de- pressed to unlock it and is rotated to bring the curved edge B over and in contact with the saw blade and allowed to again lock by the action of the spring 22. The amount the disk is rotated, depends entirely at what 110 inclination the saw blade is to be held in respect to the anvil. The curved edge B of the disk first engages the blade adjacent its non-cutting edge, which holds the blade at a slight inclination, but a further rotation of the disk causes the curved edge B to en- 115 gage the saw blade further towards the cut-

ting edge, consequently increasing the inclination of the saw blade. The varying of the inclination of the saw blade, regulates the angle or pitch at which the teeth are set.

5 After the setting of the teeth, which extend angularly in one direction from the blade, and it is desired to set the other teeth, the saw is removed by first rotating the disk to bring the straight edge A opposite the anvil so that the saw may be lifted freely from the anvil. The saw is turned inside out or reversed and replaced on the anvil in the same manner heretofore described and the disk is again rotated to occupy the same position it formerly had to insure the holding of the blade at the same inclination which permits the second set of teeth to be set at the same angle that the first set of teeth were set. Before the disk is rotated to free the saw blade, the operator notes the socket occupied by the locking pin and after the replacement of the saw blade, the disk is rotated until the pin engages the same socket, thereby insuring the holding of the blade at the same inclination as heretofore and consequently bringing about the setting of the second set of teeth at the same angle as that of the first set of teeth.

30 The eccentric mounting of the disk and the curved edge B thereof, permits saw blades of different widths to have their teeth set by the device.

What is claimed is:—

1. A saw set including an anvil, a gage and guard element for coaction with the anvil in the setting of a saw and engageable with the saw on the opposite side thereof to the anvil, and said gage and guard element being movable into and out of the path of movement of the saw for the purpose specified.

2. A saw set including an anvil, a gage and guard element for coaction with the anvil in the setting of a saw and engageable with the saw on the opposite side thereof to the anvil, and said gage and guard element being eccentrically mounted for movement into and out of the path of movement of the saw for the purpose specified.

30 3. A saw set including an anvil, a gage and guard element for coaction with the anvil in the setting of a saw and engageable with the saw on the opposite side thereof to the anvil, said gage and guard element being eccentrically mounted for movement into and out of the path of movement of the saw for the purpose specified, and said gage and guard element having a curved edge to engage the saw to tilt it.

60 4. A saw set including a base having an anvil and a hammer, a gage and guard element eccentrically and rotatably mounted on the base and having a straight edge and a curved edge, said element when positioned with the straight edge next to the anvil is

adapted to permit a saw blade to be placed on and removed freely from the anvil, said element when positioned with its curved edge next to the anvil is adapted to engage the blade to prevent it from moving upwardly 70 when a tooth is struck by the hammer and to permit the blade to be held at different inclinations.

5. A saw set including a base having an anvil and a hammer, an element eccentrically and rotatably mounted on the base and having a straight edge and a cam shaped edge, said first edge adapted to permit a saw blade to be placed on and removed from the anvil, said second edge adapted to overlie 80 and contact with the blade at different points between its cutting and non-cutting edges.

6. A saw set including a base having an anvil and a hammer, an element eccentrically and rotatably mounted on the base and having a straight edge and a cam shaped edge, said first edge when positioned next to the anvil is adapted to permit a saw blade to be placed and removed from the anvil, said element when rotated to bring the second edge towards the anvil is adapted to overlie and engage the blade at different points between its cutting and non-cutting edges, and means for locking the element in its various positions.

95 7. A saw set including a blade having an anvil and a hammer, an element eccentrically and rotatably mounted on the base and having a straight edge and a cam shaped edge, said first edge when positioned next to the anvil is adapted to permit a saw blade to be placed on and removed from the anvil, said element when rotated to bring the second edge towards the anvil is adapted to overlie and engage the blade at different points between its cutting and non-cutting edges, and means for locking the element against rotation in any of its adjusted positions and adapted to aid a person to again rotate the element from one of the saw-holding positions to a non-saw-holding position and back to the former saw-holding position.

105 8. A saw set including an anvil and a hammer, a pin mounted for adjustment relatively to the hammer, and a saw gage and guard element movably mounted on the pin for coaction with a saw blade engaged with the anvil.

120 9. A saw set including a base having an anvil and a hammer, a pin mounted for adjustment on the base relatively to the hammer, and a saw gage and guard element rotatably and slidably mounted on the pin for coaction with a saw blade engaged with the anvil.

125 10. A saw set including a base having an anvil and a hammer, a pin mounted for vertical adjustment on the base relatively to the hammer, a gage and guard element rotatably and slidably mounted on said pin 130

for coaction with a saw blade engaged with the anvil, means normally urging the element to its uppermost position, and a locking means adapted to hold said element 5 against rotation when in its uppermost position.

11. A saw set including a base having an anvil and a hammer, a substantially vertical pin mounted on the base, a gage and 10 guard element rotatably and slidably mounted on the pin for coaction with a saw blade engaged with the anvil, said gage and guard element having a straight edge and a cam shaped edge, and a locking means for holding the element against rotation and adapted 15 to permit rotation of said element under manual influence.

12. A saw set including a base having an anvil and a hammer, a pin mounted on the 20 base, a gage and guard element slidably and rotatably mounted on said pin for coaction with a saw blade engaged with the anvil, said gage and guard element having a series 25 of sockets, a second pin carried by the first pin and adapted to engage in any one of

said sockets to lock the element against rotation on the pin, and a tension means engaging said element to urge the same upwardly for causing the second pin to engage in a socket which alines therewith. 30

13. A saw set including a base having an anvil and a hammer, a pin mounted on the base, a gage and guard element for coaction with a saw blade engaged with the anvil, said gage and guard element being eccentrically and rotatably mounted on said pin and having a straight edge and a cam shaped edge, a head on said pin for limiting the upward movement of said element, tension means engaging said element for urging the 40 same upwardly, said element having a series of sockets, and a second pin carried by the head and adapted to engage in any one of the sockets.

In testimony whereof I affix my signature 45 in presence of two witnesses.

ARTHUR MANHART.
